UNITED STATES PATENT OFFICE.

EMMANUEL LA VALLEE, OF PAWTUCKET, RHODE ISLAND, ASSIGNOR TO LORRAINE MANUFACTURING COMPANY, A CORPORATION OF RHODE ISLAND.

SHUTTLE.

1,176,681.

Specification of Letters Patent. Patented Mar. 21, 1916.

Application filed July 10, 1915. Serial No. 39,179.

To all whom it may concern:

Be it known that I, EMMANUEL LA VALLEE, a citizen of the United States, residing at Pawtucket, in the county of Providence and State of Rhode Island, have invented 5 certain new and useful Improvements in Shuttles, of which the following is a specification, reference being had to the accompanying drawings, forming part thereof.

10 This invention has reference to improvements in shuttles for looms whereby the side walls of the shuttles are continuous throughout and particularly at the points corresponding to the axis on which the spindle is 15 adapted to swing.

A further object of the invention is to simplify the construction of loom shuttles with particular reference to the mounting of the spindle.

20 Other objects of the invention will appear from the following description.

The invention consists in the novel bearing for the spindle pivot.

The invention also consists in such other 25 novel features of construction and combination of parts as shall hereinafter be more fully described and pointed out in the claims.

Figure 1, represents a plan view of a loom 30 shuttle illustrating this improvement. Fig. 2, represents a longitudinal sectional view of parts of the same taken on line 2—2 Fig. 1. Fig. 3, represents a detail sectional view of parts of the shuttle taken on line 3—3 Fig. 1.

35 Similar characters of reference designate corresponding parts throughout.

In carrying this invention into practice in the preferred form herein shown I take a shuttle body A of a conventional shape exteriorly and having the usual bobbin receiving cavity B. At one end of this cavity B and extending in line therewith I provide the recess or compartment C having the side walls D, D and the end wall E having the 40 depressed top f and the shoulder g. The side walls D, D have the slots d, d which communicate with the U-shaped seats e, e constituted by semi-circular grooves, spaced from the inner surfaces of said walls D, D 45 to receive the U-shaped metallic bearing members 5, 5 the arms of which are semi-circular in cross section.

The bobbin carrying spindle 6 has the in-

tegral base 7 having the cam shoulder 8, the stop finger 9, and the transversely extending pivot pin 10 the ends of which are slidably and rotatably received by the bearing members 5, 5. In order to retain the base 7 and its spindle 6 in the shuttle I provide the recess C with the spring plate 11 secured in place by the screw 12 so that one end of said plate 11 rests against the depressed top f while the other end bears against the cam shoulder 8, of the spindle base 7 whereby, when the spindle is in the position shown in the drawings, to press the stop finger 9 of said base 7 against the shoulder g of the shuttle recess or compartment C. When the free end of the spindle 6 is swung upward, as in changing bobbins, the plate 11 coöperates with 70 cam shoulder 8 to sustain the spindle in such position.

By reference to Fig. 1 of the drawings it will be noticed that the ends of the pivot 10 do not extend to the outer surfaces of the 75 shuttle walls and cannot be displaced to positions where said pivot can act against the loom reed or any exterior part relative to which the shuttle is adapted to be moved.

The U-shaped bearing members 5, 5 for 80 the spindle pivot pin 10 are durable and are effectually retained by their seats e, e. These bearing members also facilitate the withdrawal and replacement of the pivot pin 10 with the spindle 6.

Having thus described my invention I claim as new and desire to secure by Letters Patent—

A shuttle having a spindle receiving cavity and a contracted recess extending from 90 said cavity and having an end wall furnished with a stop shoulder and side walls having grooves, U-shaped seats of semi-circular cross section in the shuttle body spaced from the walls of said recess, U-shaped 95 bearing members having semi-circular arms permanently located in said seats, a spindle having a base furnished with a cam shoulder and a stop finger, a pivot pin extending transversely of said spindle base and having its ends slidably and rotatably received by said bearing members, and a spring plate secured in said recess and bearing against the cam shoulder of said spindle base.

EMMANUEL LA VALLEE.
